HUNTER'S CAP

Irving E. Soboroff, Chicago, Ill., assignor to
 Soboroff-Rosenwald Company, Chicago, Ill., a
 corporation of Illinois

Application February 10, 1941, Serial No. 378,174

1 Claim. (Cl. 2—196)

This invention relates to caps, and more particularly to a hunter's type of cap having substantially half of its outer crown covering reversible so as to be folded over the other half when it is desired to provide the cap with a different color, such as red or the like.

In the past, in caps of the aforementioned type it has been necessary to remove the cap from the head of the wearer in order to effect reversing of the half portion having its undersurface of a different color such as red. The reason it has been necessary to remove the cap is on account of the fact that the crown is of a curved form and it is not feasible to work progressively the reversible half over the other half of the crown, unless the cap is first removed from the head of the wearer.

An object of this invention is to provide a cap which overcomes the above noted disadvantage and enables a reversal or folding of one half of the outer crown covering of the cap over the other half without necessitating removal of the cap from the head of the wearer.

In accordance with the general features of this invention, there is provided a cap including an outer crown covering having a reversible half portion foldable over the other half portion of the crown; this reversible portion being separated for a limited extent at the back of the crown from the other half portion by fastening means which is operable to disconnect and connect the half portions together whereby the reversible portion may be folded from one side of the crown to the other without requiring removal of the hat from the head of the wearer.

In accordance with the preferred embodiment of my invention, I provide the fastening means in the form of a slideable type fastener or "zipper" disposed in substantially the medial plane of the cap and extending only part way up the back of the crown.

Other objects and features of this invention will more fully appear from the following detailed description taken in connection with the accompanying drawing which illustrates a single embodiment thereof, and in which:

Figure 1 is a rear perspective view of the cap showing it applied to the head of a person;

Figure 2 is a fragmentary view of the rear portion of the crown of the cap showing the reversible half detached from the other half and in the process of being folded upwardly; and

Figure 3 is a view showing the reversible half portion of the outer crown covering completely turned or folded over the other half portion and

the fastening means in the process of being moved to its connecting position.

As shown on the drawing:

The reference character 10 designates generally the crown of a so-called "hunter's type" of cap which includes the usual button 11 at the top, as well as the visor 12 at the front. These caps are usually made of brown corduroy, and I have accordingly so illustrated it in Figure 1.

10 The crown 10 of the cap includes an outer covering comprising two half portions 13 and 13a. The half portion 13 is adapted to be reversed in position or, in other words, progressively folded over the top of the crown onto the other half 15 13a. In Figure 2, I have illustrated how this reversible half 13 is initially turned or folded upwardly in the process of starting to reverse its position. It should be noted that the under surface 14 of the reversible half portion 13 is of a different color than the normal color of the cap. 20 For example, this surface 14 may be red which is the usual practice and as I have illustrated it.

Since it is desired to change the color of the crown of the cap from, for illustration, brown to red, it follows that if the undersurface 14 of the reversible portion 13 is red, the surface 15 of the half of the crown underneath the foldable portion 13 must likewise be red. Thus, when the reversible or foldable half portion 13 is completely turned over to the other side or half of the cap, as shown in Figure 3, the outer surface of the entire crown will then be of red color.

As I have noted before, considerable difficulty has been experienced in effecting this folding or reversing operation in hunter's caps, and as a consequence it has been necessary to remove the cap from the head of the wearer in order to effect the desired folding operation.

In order to facilitate this action, as well as to 40 eliminate the necessity of removing the cap from the head of the wearer, I partially separate the two half portions 13 and 13a from each other at the back of the crown and to a limited extent. This is effected by providing a short length fastener, designated generally by the reference character 16, and which is disposed in substantially the medial plane or seam of the crown. I have illustrated this fastener as being in the form of a slideable or "zipper" type, and it will be 45 noted from Figure 1 that it only extends part way up the back of the crown.

In order to change the color of the crown from say brown to red, the first step necessary in the operation is to disconnect the fastener by 50 pulling upwardly on the handle or finger grip 17.

Then, the rear end of the reversible portion 13 may be slightly turned upwardly, as shown in Figure 2, and thus worked progressively over the top of the crown until it is completely over the other half portion 13a, as shown in Figure 3.

Thereafter, the slight gap between the two half portions 13 and 13a at the back of the crown may be closed by pulling the handle 17 of the fastener downwardly, thus connecting the two overlapped edges of the two half portions 13 and 13a at their place of separation.

This operation of connecting and disconnecting the fastening means, as is readily evident, may be easily effected by simply sliding the "zipper" handle 17 up or down as the case may be and does not necessitate removal of the cap from the head of the wearer in order for the desired folding of the reversible half portion 13 to be effected. To return the reversible half portion 13 from the

position shown in Figure 3 to the position shown in Figure 1 merely requires that the reverse of the operations, above described, be followed.

I claim as my invention:

5 As an article of manufacture, a cap comprising a crown including a covering having a reversible half portion foldable over the other half of the crown, said reversible portion being separated for a limited extent at the back of the crown from the other half portion by fastening means which is operable to disconnect and connect said portions, whereby said reversible portion may be folded from one side to the other of the crown without requiring removal of the cap from the wearer, said fastening means comprising a slideable type of fastener disposed in substantially the medial plane of the cap and extending part way up the back of the crown.

IRVING E. SOBOROFF.
